UNITED STATES PATENT OFFICE.

FRANK M. SLOUGH, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

TELEPHONE-EXCHANGE SYSTEM.

Application filed January 24, 1918. Serial No. 213,473.

To all whom it may concern:

Be it known that I, FRANK M. SLOUGH, a citizen of the United States, residing at Rochester, in the county of Monroe and

5 State of New York, have invented a certain new and useful Improvement in Telephone-Exchange Systems, of which the following is a full, concise, and exact description.

This invention relates to telephone exchange systems, and more particularly to that type of exchange systems in which calls are automatically extended by mechanical means to different idle call receiving apparatus.

10 15 One of its objects is to provide for the automatic distribution of incoming calls to different operators' positions in a manual switchboard, the distribution being in rotation, that is, calls will come in to call receiving circuits one after another in a given order not departing from this, unless some of the call receiving circuits are manually disabled as will be described later.

Another of the objects of the invention is 20 25 to provide a conversational circuit from the calling subscriber's line to the operator's call extending apparatus independent of the call receiving apparatus over which the subscriber has given his order.

30 35 Another object is to release the call receiving apparatus for use in receiving an order pertaining to another call after the first order has been received, and the manual switching function performed by the operator. In this way I am enabled to use a small number of call receiving circuits common to a number of line circuits.

Another object of the invention is to provide for a manual selection of idle call extending circuits which may be cord circuits, the selection being made by the operator, and by the attaining of this object I cause the operator to be enabled to manually pre-select the call extending or cord circuit which she can do prior to answering the call, and time is thereby saved.

40 45 Other objects of my invention and the invention itself will be more clearly understood from a description of the embodiment illustrated in the drawings which are a part of this specification.

The particular embodiment of the invention herein described will be understood by reference to the accompanying drawings 55 wherein—

Fig. 1 shows a plurality of telephone lines, herein illustrated as two telephone lines, the central office apparatus individual to these lines being shown, and the station apparatus of one of the lines being shown in Fig. 1, and of the other line being shown in an extension of Fig. 1 on the sheet of drawing containing Fig. 5.

Fig. 1 also shows a system of interconnecting intersection trunks for the purpose 60 65 of extending a call originating on one of the lines to one of a plurality of interconnecting trunk circuits shown in Fig. 3.

Fig. 1 also shows the means for extending what I term code wires from the impulse 70 apparatus shown in Fig. 2 to code conductors of the interconnecting trunk circuit, the particular code wires thus extended depending upon the particular line which is calling.

Fig. 2 illustrates a system of code inter- 75 rupter wheels whereby current impulses or, in other words, circuit interruptions are caused to be made, there being a wheel for each number from 1 to 10, and there being four groups of the said wheels to denote 80 thousands, hundreds, tens, units, and numerals or calling line numbers. Code wires extend from these interrupter wheels to the lines as illustrated in Fig. 1, one code wire of each digit being associated with each telephone line. A master impulse wire is also extended from Fig. 2 to Fig. 4 to mark the beginning of a train of impulses and the end thereof, the same train of impulses being composed of consecutive series of interruptions from the different orders of code wires. 85

Fig. 3 illustrates a system of interconnecting intersecting trunks similar to that shown in Fig. 1, one of the sets of trunks being extended from Fig. 1, and the other system of 90 95 trunks capable of being connected thereto under the control of the controlling apparatus also shown in Fig. 3 to call receiving trunks or circuits which are extended to Fig. 4.

Fig. 4 shows the extension of the call receiving circuits from the disclosure of Fig. 3 100

and operative apparatus individual thereto whereby an operator may be connected to the call receiving circuit to receive a call, and to ascertain the number of the called line desired by the party on the calling line.

Fig. 4 also illustrates a plurality of connective apparatus associated with the call receiving circuits whereby the said call receiving circuits may be connected to one of a plurality of plug connecting circuits, two of which are also shown in this figure. At the left of Fig. 4 are shown connecting plugs which are of the manually operated type, and which plug connecting circuits terminate. On the right side of Fig. 4 is shown the automatically operated apparatus associated with the said plugs, whose functions will be later described.

Fig. 5 shows electrically operated automatic switches with circuit conductors and controlling apparatus for the said switches whereby line talking conductors, such as the talking conductors 111 and 112 are extended thru contacts of the said switches to the terminals *cc* and *dd* of a telephone line having line conductors *c* and *d*, and as shown in the drawing of Fig. 5 having a substation A connected to the said line conductors. In the drawing of Fig. 5 showing this system, 111 and 112 represent the extended talking conductors of the connected circuit CP shown in Fig. 4. 203 and 204 represent normally open contacts in the automatically selected connecting circuit which are closed immediately following the association of the said connecting circuit with the plug connecting circuit of Fig. 4. 205 is the impulse relay by means of which the various numerical switches are set under the control of actuating impulses received over the conductor 110 and thru the intervening contacts in its circuit produced by the contacts 13 of the relay 12 shown in Fig. 1, as has been described; the said impulses by means of the impulse relay 205 being transmitted to the stepping magnets of the switches. Batteries of different potential are indicated in the drawing of Fig. 5. Certain of these batteries which are indicated as being merely of two cells, may be of 24 volts potential, the other batteries indicated as being of 4 cells, may be of 48 volts potential. A selective system producing equivalent results to that shown in Fig. 5, and having a source of current of but one potential may be employed instead of that illustrated.

When this apparatus is taken for use by the manual selective act of an operator, the apparatus is so arranged that current impulses will be transmitted over a private circuit conductor leading from the right of Fig. 4, and which is extended to Fig. 5 to operate selective switches of an automatic selective system which may be any of the

common types known to the art and which in the embodiment illustrated in this description is illustrated as being such a system as that illustrated and described in the patent to A. E. Lundell, No. 1,194,851, granted August 15, 1916, whereby the apparatus of Fig. 4 controls the apparatus of Fig. 5 to connect to the talking conductors which are extended from Fig. 4 thru the apparatus of Fig. 5 the talking conductors of the calling line.

The current impulse apparatus of Fig. 4 is operated under the control of the code apparatus of Fig. 2, circuit conductors from which are extended by means of the apparatus of Figs. 1, 2 and 3 to that of Fig. 4.

Referring now to the figures, Fig. 2 shows code impulse apparatus herein illustrated as composed of a series of interrupter wheels making interrupted contact with contact springs, these interrupter wheels being arranged in four groups which I term units, tens, hundreds and thousands groups. In each group are ten interrupter wheels, each in a complete rotation of the wheel carrying shaft which may be common to all of the wheels, but which shaft has been omitted in the drawing for the sake of clearness, causing the contact springs to be opened from one to ten times, depending upon the particular interrupter wheel. Preferably the interrupting segments of the wheels are so arranged that none of those of the second or tens set will be operated during the operative period of those of the first set, and the same is true of the third and fourth sets; that is, each set will produce its contact interruptions one after the other, the thousands operating first, the hundreds second and tens third and the units last in order, there being a time interval between the operation of each successive group.

Code wires extended between the contact springs operated by a different interrupter wheel to apparatus associated with the subscribers' lines shown in Figs. 1 and 5, and the current impulses produced by the interrupter wheels are relayed thru apparatus of the subscribers' lines brought into action by the act of a subscriber making a call, to a conductor of a call receiving circuit, such as illustrated in Fig. 4, the combination of code wires for each of the lines being different from the combination of any other of the lines. This arrangement provides means whereby automatic apparatus brought into action by the act of an operator in making connection with a called line by the use of one of the connecting circuits of Fig. 4, may while the said connecting circuit is associated with the call receiving circuit conveying the call, cause the said current impulses produced by the code interrupter wheels of Fig. 2 which interruptions are relayed to the apparatus of Fig. 130

4, cause the said apparatus to so control the automatic selective switch mechanism of Fig. 5 to cause it to make a connection between the operative terminals of a 5 calling line to the operative terminals of the plug connecting circuit whereby the plug connecting circuit finally establishes connection between calling and called lines, independent of the first established circuit 10 from the calling to the call receiving circuit; which first established connection is merely for the purpose of an instruction call circuit for the use of the operator in learning the wishes of the calling subscriber.

15 In the embodiment illustrated, I show apparatus to select the particular call receiving circuit to be used for a given incoming call, the selecting apparatus illustrated in Fig. 3 providing for the consecutive selection 20 of call receiving circuits. These call receiving circuits may be distributed among a plurality of operators and a sufficient number provided so that by the apparatus as selected by all of them many of the first selected call receiving circuits will have been 25 discharged from use by the connective act of operators, and again be conditioned to receive new calls.

In this way I obviate the necessity of complicated interconnecting apparatus for these 30 call receiving circuits to select busy or non-busy call receiving circuits, and I also by this means provide a very even distribution 35 of the calls throughout the entire switchboard.

In order to reduce the number of such 40 call receiving circuits necessary, I provide means under the control of an operator to limit the time of use of each call receiving circuit, that is, the call receiving circuit is not required to be used for the period of 45 conversation between connected subscribers' stations, but only until such a time as the subscribers are connected together in conversational circuit, the call receiving circuit then reverting to its idle condition, being dissociated from the connection circuit 50 from which it is thereafter independent during the period of the conversational connection previously set up.

I also provide for each operator's position 55 a plurality of interconnecting circuits, whereby an operator may manually select one of the said interconnecting circuits. The selected interconnecting circuit will thereupon under the control of the identifying means above referred to thru the intervening call circuit cause selective switches of an automatic selective switching system 60 to operate to connect the calling line directly thru the said switches to the interconnecting circuit. The call receiving circuit is thereupon discharged from the connection and the subsequent operation of the interconnecting circuit is very much like that of

a cord circuit in the ordinary manual telephone system, the called-for subscriber being signaled and the supervising of the connection being taken care of by signal lamps within the view of the operator, and the 70 operator having access to the connection by listening keys and capable of severing the connection by disabling the connection switch of the interconnecting circuit.

Having thus described my invention in 75 its broadest aspects, I will now describe the specific embodiment thereof illustrated in the drawings accompanying this specification, and will also describe the operation of the system from which other objects of my 80 invention than those above referred to will be apparent.

Referring now to Fig. 1, at L and LL, I show central office apparatus individual to two telephone lines extending from substations shown at AA for the line LL, and at A in Fig. 5 for the line L. Circuit conductors a, b, c, d, extend from the line circuit L to like referenced conductors of Fig. 5 in which figure multiple jacks J1 and J2 are 90 provided for the line L, and connector switch contacts cc, dd and bb are likewise provided for the line and shown in Fig. 5, the conductors c and d being the line talking conductors that lead from the apparatus 95 of Fig. 1 to the substation apparatus at A on Fig. 5.

Assume now that the subscriber on the line L whose substation apparatus is shown at A, desires to make a call, he will do so 100 by removing the telephone receiver r from the hook closing the switchhook contacts s, and closing a circuit thereat to bridge the line conductors c and d which lead from that portion of the line circuit shown in Fig. 5 105 to the line apparatus of the line L shown in Fig. 1, and thru normal contacts 1 and 3 of the line cut-off relay C and the battery feed tandem windings 4 and 5 of the relay 6 to the positive and negative poles of the 110 central office source of current, from which source current will flow thru the said windings over the said line to supply energizing current for the transmitter of the substation A, and to operate the relay 6. The relay 115 6 will thereupon attract its armatures closing contacts 7, 8, and 9 in circuits to be described. The contacts 8 and 9 being closed two co-operating circuits will be thereby completed thru the windings 10 and 11 of 120 the relay 12 which may be called the line impulse relay, which circuit includes the four circuit conductors u, t, h and th. These symbols relate to the units, tens, hundreds and thousands digits of the number 125 characterizing the subscriber's line L with which the thereby referenced circuit conductors are associated. Similar circuit conductors to u, t, h and th for the line L are provided for all of the lines of the system being 130

described, the conductors *uu*, *tt*, *hh* and *th*—*th* designating like conductors for the line LL.

This description will be confined to the operation of the system wherein the line *L* is the calling line, and the line LL is the called line of a circuit connection to be established, and the establishment of which connection is described.

- 10 At the lower part of the sheet of Fig. 1 are shown four groups of circuit conductors, there being ten circuit conductors in each group. These circuit conductors I term code wires, the first group of code wires being for 15 the purpose of providing the units designation of any telephone line, the second group being provided to designate the tens digit of a telephone line, the third group the hundreds digit and the fourth group the thousands digit thereof. These code wires are shown extended from Fig. 1 to Fig. 2, and on Fig. 2 are shown the code interrupting wheels for each of the circuit conductors of the four groups. Other circuit interrupting 20 mechanism than that specifically shown in Fig. 2 may be associated to perform the functions required of the specific structure shown in Fig. 2. In the embodiment illustrated the code impulse wheels are assumed 25 to rotate synchronously as on a common rotating shaft together with a master impulse wheel *w* shown to the left of the four groups of impulse wheels in Fig. 2. The bottom row of impulse wheels shown in Fig. 2 are 30 connected in electrical circuit with the ten code wires of the group TH, each conductor of the ten in the group being connected to a different impulse wheel; the bottom conductor of the group shown in Fig. 2 leading 35 to an impulse wheel TH-1, and the top code wire of the thousands group leading to the impulse wheel TH-10, the first named impulse wheel having a single short circuit interrupting insulating piece in the periphery of the conducting segment thereof, and the last named impulse wheel having ten 40 short circuit interrupting insulating pieces in the periphery of its circuit conducting segment; the other intermediate code wires being connected to impulse wheels having different 45 numbers of insulating circuit interrupting pieces, from two to nine pieces in the various wheels, these insulating pieces being so arranged as shown in the drawing 50 in what may be called the first quadrant of the wheel circumferences. The conducting segments of all the wheels of this first named group are connected to the negative pole of the central office source of current, and 55 the hundreds next above the thousands group of wheels like insulating pieces are arranged in the circuit conducting segments, only they are placed on what may be termed the second quadrant of the wheel. 60
- 65 It will be noted that between the first and

second quadrants in each group of wheels above mentioned, there is a circuit conducting space on the periphery of the wheels considerably broader than the circuit conducting spaces between the insulating pieces. 70 The two other groups of the wheels for the tens and units designations are like the wheels of the thousands and hundreds designations just described, only the circuit conducting portions and the insulating pieces 75 are arranged just 180 degrees away from the like portions of the before described wheels. In this way four wheels for like digits in the different groups will produce a like number of circuit interruptions, only the circuit interruptions will not occur simultaneously, being produced in regular order one after the other as the four circuit interrupting quadrants come successively 80 under the brushes attached to the code wires 85 which are all arranged in the embodiment illustrated to contact on the same side of the wheels. The circuit conducting segment of the thousands as has been described, is connected to the negative pole of battery, the hundreds group to the positive pole of battery, the tens group to the negative pole of battery, and the units group to the positive pole of battery.

The impulse relay 12 of Fig. 1, has its 95 windings 10 and 11 placed in series with the units and hundreds, the tens and hundreds code wires, respectively, by the operation of the relay 6 closing contacts 8 and 9 as before described and each wheel of the two pairs 100 producing current impulses of different polarity. It is apparent that current impulses will be produced in the circuits described, thru the said windings 10 and 11, producing sets of magnetic impulses one after the other 105 in the core of the said relay, so that the contacts 13 thereof will be vibrated to produce successive trains of current impulses characterizing the four digits comprising the number of the calling telephone line. The short 110 contact piece of the wheel W which is connected to the ground pole of battery as will be later more fully described producing a single impulse of current over its connected 115 conducting wire after the associated circuits as will be later described are properly conditioned, the timing of this single current impulse being such that it will occur just before the thousands train of circuit interruptions begin. The circuit conductor leading 120 from this master impulse wheel leads to the interconnecting circuit mechanism of Fig. 4 which will be later described.

When the relay 6 was operated contacts 7 were also closed completing a circuit from 125 the negative pole of battery, thru the resistances 14 and 15 to the ground pole of battery, and thereby raising the electrical potential of the circuit conductor 16 leading thru the winding 17 of the line cut-off relay 130

C of the line and the circuit conductor *a* leading to like referenced circuit conductor *a* of Fig. 5 to the thimbles of the multiple jacks *J*1 and *J*2 of the calling line. This 5 raises the electrical potential of the said multiple jack thimbles and conditions the line to test busy when the ordinary manual busy test is made by touching the plug of an interconnecting circuit to the said thimbles 10 in the usual manner. A branch circuit is also closed by the contacts 7, the circuit being traced thru the said contacts and a winding 18 of a connection relay 19, and thru normal contacts 20 of a relay 21 to the 15 ground pole of battery.

The object of the completion of the circuit just traced is to interconnect circuit conductors *c*, *d* and *f* of the calling line to an intersecting trunk circuit, such as the trunk circuit 20 B or the trunk circuit D, the trunk B in the description being taken as the seized trunk circuit, but if the trunk circuit B is busy, that is, taken for use by another line such as the line LL, the relay 21 would have 25 been operated, and the contacts 20 opened so that the circuit just traced including a winding 18 of the relay 19 would not have been completed, but instead a circuit would have been completed comprising a winding 30 18 D of a relay 19 D, the circuit being established thru contacts 20 D of a relay 21 D, all associated with the trunk D, and having parts which correspond to parts referred to for the trunk B. Likewise if the trunks B 25 and D were busy, the next succeeding trunk would be seized for use upon the initiation of the call by the subscriber at A as described. The circuit just traced being completed, current will flow over the same from 40 the source of current included in the circuit thru the winding 18 of the relay 19 and then will cause this relay to be energized thereby attracting its armatures and closing contacts 22, 23, 24 and 25.

45 The contacts 22 being closed a holding circuit is thereby established for the relay 19, including its winding 26, the circuit being traced as follows: From the negative pole of the source of current, the now closed contacts 7 of the relay L, the winding 26 of the relay 19, the now closed contacts 22 thereof, the winding of the relay 21 which is individual to the trunk circuit and common to the group of lines capable of being connected to the trunk; the circuit being thereafter traced thru conductor R which leads to a like referenced conductor R on Fig. 3, where the circuit of the trunk line may be seen extended, and thru the winding of the relay 27 50 to the ground pole of the source of current. This will cause the operation of the relay 21 to open contacts 20, whereby another line may not be connected to the trunk line B, and will cause the contacts 28 to be 55 closed extending the circuit of the connect-

ing ground or the trunk seizing circuit to contacts of a like relay for the trunk circuit D which is assumed to be the next succeeding trunk circuit capable of being seized for use by a calling line. The relay 27 will also 7 be operated in series with the relay 21, and will attract its armatures closing contacts 29 and 30. The contacts 29 being closed, a circuit will be completed including the said contacts traced as follows: From the negative pole of the source of current thru the said contacts 29 and winding 31 of the relay 32, contacts 33 of a relay 34, a brush 35, a contacting segment 36 of a rotary switch SW, and thence thru the winding of a relay 37 to the ground pole of battery. This circuit being closed, current will flow over the same operating the relay 37, which being of very high resistance will so limit the strength of current flow that the serially included winding 31 of the relay 32 which is of relatively low resistance will not energize the relay 32 sufficiently to operate its contacts. The relay 32 and a like relay 132 for the trunk line D are arranged to interconnect a 90 call receiving circuit M to the associated trunk line B or D.

In this description, although but two trunk lines of each type are shown, it is understood that other trunk lines might be employed in practice to increase the volume of service, as may be required of the trunks. 95

The relay 34 is individual to the call receiving trunk line circuit M and is common to all of the trunk lines B and D which may have access to the trunk M. The switch SW and the associated magnets 37 and 38 together with associated apparatus is common to all of the call receiving trunk lines, such as M and N shown in the drawing of Fig. 3, and operated to condition a next succeeding call receiving circuit for a subsequent call upon establishment of a preceding call connection whereby an incoming trunk line, such as B or D is connected to 100 a call circuit. 105

It is understood that other forms of interconnecting switch mechanism may be employed to produce the inter-connection of the trunk lines of the various types, such as 115 rotary switches or cross-bar switches, as are a part of the art.

The relay 37 having been operated, the contacts 39 thereof will be closed completing a circuit including the source of current, and the slow releasing magnet 38 which is the motor magnet for the switch SW, the switch SW being of the back stroke type, being propelled from one operative position to another upon the de-energization of the 120 slow releasing magnet 38, which may be made slow releasing in any suitable way. The magnet 38 being operated, the armature thereof will be attracted and will cause the carried pawl to fall into the next succeed- 125 130

ing notch of the ratchet wheel RW, so that upon the de-energization of the magnet 38 which now takes place, the ratchet wheel RW will be propelled by the action of the spring 40 to its next position of rest causing the next operative position of the switch SW. The magnet 38 being energized, contacts 41 will be closed upon a full attraction of the armature short circuiting the high resistance relay 37. This will produce a slow releasing of the armature of the relay 37 and of the slow release relay 38, but in the meantime will accomplish the operation of the relay 32 by increasing the flow of current 15 from its winding 31 in the circuit which has been described.

The relay 32 having been operated, a locking circuit will be completed therefore including contacts 42 and a winding 43 thereof, and windings of the relays 34 and 44 of the call receiving circuit, the relay 44 being shown in Fig. 4. This locking circuit is traced as follows: From the negative pole of the source of current, thru the contacts 30 of the relay 27, the contacts 42 and the winding 43 of the relay 32, the winding of the relay 34, circuit conductor Ro which is shown in Fig. 4, and the winding of the relay 44 to the ground pole of the source of current. Current from the said source will flow over the said circuit, causing the relay 32 to remain operative and causing the operation of the controlling relay 34 and the relay 44 of the call receiving circuit. The relay 34 being operated, contacts 33 thereof will be opened to open the circuit leading to the relay 37, and also to open the common circuit of the trunk seizing windings as 31 and as 131 of such another trunk connecting relay as 32 and 132, so that the call circuit cannot be taken for use by another incoming call of another trunk. The relay 44 being operated will close its contacts 45 and 46, the contacts 46 completing a circuit for the answering signal lamp 47 thru normal contacts 48 of a relay 49, this circuit including the source of current, and the lamp 47 will be operated to apprise the operator that a call exists on the call receiving circuit M, with which the lamp 47 is associated.

Another call receiving circuit is shown at X in Fig. 4 for the same operator's position. Other call receiving circuits, such as N shown in Fig. 3, lead to call answering apparatus on other operators' positions. The call circuits M, N and others not fully shown in Fig. 3, but which it is understood may be included in the system of my invention lead 55 to other operators' positions, the preferred order in which these call receiving circuits are allotted for the use of succeeding incoming calls by the call allotting switch SW, being such that the first call receiving 60 circuit of the first operator will first receive

a call, then the first call receiving circuit of the second operator, and then so on until all of the operators have had a call associated by the call allotting switch SW in the first call circuit of each operator's position. Thereafter the said call allotting switch will allot calls to the second call receiving circuit in order to each position until calls have been allotted to all call receiving circuits, which preferably may be five in number for certain conditions in telephone traffic which are obtainable in practice, whereupon the call allotting switch SW will again allot a call to the first call circuit of the first operator and so on, it being proposed to thus distribute the calls in absolute rotation as to call circuits and as to operators' position.

The line talking conductors c and d of the calling line have now been extended by means of contacts 23 and 24 of the relay 19 of Fig. 1, and by contacts 50 and 51 of the relay 32 of Fig. 3 to the listening key springs 52 and 53 of the listening key 54 of Fig. 4. The operator may now answer the call on the call receiving circuit M, by operating the listening key 54 and closing the contacts thereof to connect her operator's telephone set shown at O, to the talking conductors of the telephone line extended as described. The operator conversing with the subscriber will learn the number of the called-for line. In the operation of the listening key contacts 55 were closed completing a circuit for the relay 49, the said circuit including the source of current, the winding of the said relay, said contacts 55 and contacts 45 of the operated relay 44. This will cause the relay 49 to be operated, which immediately closes the locking circuit for itself including its winding and its contacts 56, independent of the contacts 55 of the listening key. The listening key may now be opened, the relay 49 remaining operated thru its locking contacts. The signal lamp 47 is extinguished and a signal lamp 57 will be lighted in its place to indicate that the call on the call receiving circuit M has been answered, but the desired connection not yet completed.

The circuit for the lamp 57 includes now closed contacts 58 of the relay 49 and normal contacts 59 of the relay 60, and contacts 46 of the relay 44 together with circuit conductors leading thru the said contacts, and including the source of current. The operator having learned the number of the called-for line, will now complete the connection by means of one of a plurality of connection switches under her control and which are herein illustrated as being plug and jack manually operated switches. The operator may use any connecting plug of the group provided for the purpose, and time is thereby saved in completing connection, since an operator upon completing one con-

nection by manipulating one connection plug, may immediately manually preselect the plug for the next connection by picking up such a plug as she desires to use for the 5 next connection.

In the illustrated form of my invention I arrange multiple jacks of the called lines on the operator's position in proximity to the said plug whereby the operator may by inserting the plug into the said multiple jacks make connection with called lines. Such an act will cause an association of the call receiving circuit last attended and the particular plug circuit manually selected. This is 10 not a permanent association as will be seen from the further description.

To continue the narrative, the operator having manually selected an idle plug circuit will make the busy test in the usual way by touching the tip of the connecting plug, such as the connecting plug P1, to the thimble of the called line jack which we will assume is the jack J3 for the called line LL, shown in Fig. 1. If the called line is busy, 20 the busy condition of the line will be indicated to the operator by the existence of a raised potential of the jack thimble of the jack J3 with reference to the potential of the ground pole of the exchange source of 25 current. This is accomplished by the means shown and described for the line L consisting of the contacts 7 of the relay 6, the resistance coil 14, and the winding 17 of the relay C which provided a circuit from the 30 negative source of current to the thimbles of the line jacks J1 and J2; or it may be done by a connecting plug being previously placed in one of the multiple jacks of the line, such as the jack J4, whereby the shank 35 of the plug to which is connected a circuit leading to the negative pole of battery makes contact with the said thimble to raise the potential thereof. If the line is busy, current from the said negative pole of the 40 source of current will when the busy test is made, traverse the tip of the talking strand 61 of the connecting circuit CP thru normal contacts 62 of the relay 63 and normal contacts 64 of the relay 65 to the common test 45 relay for the operator's position 66, and thru the said relay to the ground pole of the source of current, energizing the said relay, causing it to close its contacts 67 and thereby establishing a circuit for the flow of current from the source of current including an 50 inductive winding 68 on the operator's induction coil inductively related to the operator's receiver 69, which will thereby be operated giving the characteristic busy click. 55 The operator will thereupon tell the subscriber that the line desired is busy. The subscriber by restoring his receiver to the hook will open the contacts of the hook-switch, releasing line relay 6 which by its 60 contacts operated the relays which have been

described as having been operated in the establishing of this connection to the present point of description, and these relays will therefore be released restoring the apparatus to normal. If, however, the operator 70 does not in making the usual busy test find the line busy, she will insert the plug P1 for the connecting circuit CP into the jack J3 of the called line making connection thereby with a pair of talking conductors of the 75 line and a local private wire of the line circuit to like talking conductors and a private wire of the connecting circuit CP. A circuit will thereupon be closed including a winding 70 of the cut-off relay 71 of the 80 called line and the winding of the relay 65 for the connecting circuit, the said circuit including the source of current, and current from the said source will flow over the said circuit energizing these relays which will attract their armatures.

The contacts 72 and 73 of the relay 71 of the line circuit will be opened to remove the normal association between the call initiating apparatus of the line circuit and the line 90 circuit proper. The contacts 74 of the relay 71 will be closed placing the winding 75 of the relay 71 in multiple with the winding 70. The relay 65 of the connecting circuit CP shown in Fig. 4 being operated will close 95 its contacts 76, 77, 78 and 79 and open its contacts 64. The opening of the contacts 64 will dissociate the busy test relay 66 from the connecting circuit. The closing of the contact 76 will complete the connection of 100 the tip supervisory relay winding 80 to the talking strand 81 of the connecting circuit. The closing of the contact 77 will complete a circuit including the source of current and normal contacts 82 of the relay 83 for the 105 supervisory lamp 84 lighting the said supervisory lamp. The closing of the contacts 79 will complete a circuit to associate the connecting circuit CP temporarily with the incoming call circuit M, the said establishing 110 circuit including the said contact 79 of the relay 65, the contacts 85 of the relay 86, the winding 87 of the relay 88, normal contacts 89 of the relay 60, and now closed contacts 91 of the relay 49, and the source of current 115 which being in said circuit will cause a current flow over the same energizing the relay 88. This relay 88 is a called circuit interconnecting relay, and will close its contacts 93 and 94. The contacts 94 being closed a 120 holding circuit for the relay 88 will be completed, the said holding circuit including the source of current, the winding of the relay 86 of the connecting circuit and winding 95 of the relay 88, the winding of the 125 relay 60 of the called circuit, and now closed contacts 46 of the relay 44 of the called circuit. The establishing of this holding circuit including the windings of the relays 60 and 86 causes by the breaking of the con- 130

tacts 85 of the relay 86 and of contacts 89 of the relay 60, the breaking of the establishing circuit previously described at two points, one of which is located in the connecting circuit CP, the other in the called circuit M.

The contacts 59 of the relay 60 are now broken extinguishing the signal lamp 57 to indicate the association, which association is perhaps more directly indicated by the lighting of the signal lamp 96 which is included in a circuit with the source of current and now closed contacts 97 of the relay 60. This lamp 96 will remain lighted during the full period in which the talking conductors of the connecting circuit are extended by the operation of automatic selective apparatus to make connection with the talking conductors of the calling line as will be described.

The contacts 98 of the relay 86 are now closed completing a circuit from the common master impulse wheel shown in Fig. 2 and indicated at *w*, the circuit being only completed at such intervals as occur when the short segment 99 makes contact with the brush 100 to mark the intervals between successive trains of code impulses denoting calling line number designations. As soon as the contacts 99-100 of the rotating impulse wheel make contact, a circuit is completed from the ground pole of battery, thru the said segment and brush of the impulse wheel, circuit conductor *ww* leading from Fig. 2 and extended in Fig. 4, the said circuit being completed thru contacts 98 of the relay 86, normal contacts 101 of the relay 102, the winding of the relay 103 to the negative pole of the source of current thru contacts 78 of the relay 65. Current flowing over this circuit will operate the relay 103. This relay being operated will close its contacts 104.

When the line conductors *c* and *d* of the calling line were extended by means of contacts 23 and 24 of relay 19 of Fig. 1, and by contacts 50 and 51 of the relay 32 of Fig. 3 to the listening key springs 52 and 53 of the listening key 54 of Fig. 4, as has been previously described, a circuit was also completed to extend in like manner the circuit conductor *f* which I call the impulse wire from the intermittently operated contacts 13 of the relay 12 of the calling line circuit thru contacts 25 of the relay 19, thru contacts 105 of the relay 32 to the conductor 106 of Fig. 4, and which conductor 106 is later further extended by the closing of contacts 93 of the relay 88 upon the insertion of the plug P1 into the jack of the calling line; the extension being made thereby to the conductor 107 leading thru normally closed contacts 108 of the relay 109 shown in Fig. 4, and now thru the contacts 104 of the relay 103, the said contacts having been

closed as described by the operation of the relay 103, and over circuit conductor 110 of Fig. 5, and thru the winding of the stepping relay 205 to the negative pole of a source of current shown in Fig. 5.

The series of interruptions produced by the contacts 13 of the relay 12 shown in Fig. 1, will now cause the stepping relay 205 to retract its armature opening the circuit for relay 215 which in turn retracts its armature. Relay 216 being slow to release remains up throughout the series of impulses. With each deenergization of the relay 215, a circuit is completed from the 48 volt battery through the primary stepping magnet 217 and the escape relay 218 in parallel, and thence through the front contact and armature of relay 216 and the back contact and armature of relay 215 to ground. Magnet 217 and relay 218 will both be energized, and relay 218 will close a circuit from battery through the left winding of the escape magnet 214, armature and contact of relay 218, wiper 219 and the right winding of magnet 214 back to battery, thus energizing the escape magnet. The side switch, however, will not be operated this time until the escape magnet is deenergized. Relay 218 being slow to release is held up during the series of impulses. Magnet 217 rapidly attracts and retracts its armature, moving the brushes 209, 210 and 211 of the selector switch from group to group of the trunk terminals.

Upon the termination of the series of impulses, relay 205 will remain energized, and will hold the circuit for relay 215 closed. Relay 218 will then retract its armature, opening the circuit for the escape magnet 214 and causing the side switch to move to position 3. As the side switch moves to position 3 the circuit for relay 215 is interrupted, and it retracts its armature, but a substitute circuit is completed for the holding relay 216 through the side switch wiper 213 in position 3, thus preventing the release of the switch.

The escape magnet 214 is employed as a test relay. In position 3 of the side switch, a circuit is closed from the 24 volt battery through resistance 220, wiper 219 and the right winding of relay 214 to ground. The current flowing over this circuit, is however, insufficient to cause magnet 214 to pull up its armature. At this time a circuit is closed from battery through the left winding of magnet 214 and wiper 221 to the test brush 209 of the selector switch. The test or guarding contacts of trunks leading to idle selector switches will be connected to ground through a side switch wiper as 13' at the second selector and the left winding of the escape magnet 214' of that switch. If, however, a trunk leading to such switch is busy, its test or guarding contact will be provided with battery potential. This may be sup-

plied in several different manners, depending on the stage of operation of the switch which has selected the connecting circuit, and of the switch at which the circuit terminates.

- 5 If the connecting circuit has just been selected at one of its multiples and the side switch of this connecting circuit has moved to position 2, it is obvious that the test contacts will be connected to the 48 volt battery through wiper 13' and stepping relay 215'. At this time, however, the 24 volt battery at the impulse relay 205 will also be connected to said test contact by a circuit extending through wipers 213 and 221, in position 4. Therefore, the potential of the test contact will be of substantially 24 volts, the current will therefore not flow through the left winding of magnet 214 in such a manner as to cause its energization. If the 20 impulse wheel connected to the connecting circuit is at this time transmitting impulses, the battery at the impulse relay 205 will be removed from the multiple test contacts of the connecting circuit with each deenergization, 25 leaving only the 48 volt battery at relay 215 associated with said contacts. The flow of current, however, from this battery through the left winding of magnet 214, is in a direction to oppose the 30 flow of current through its right winding, and magnet 214 will not be energized. If the side switch wiper of the switch at which the connecting circuit terminates is in position 3 or position 4, the same condition will 35 exist, except that the test contact will be connected to the 48 volt battery through relay 216' instead of through relay 213'. If the switch associated with a multiple of the connecting circuit is just in the process of testing and the side switch has not yet moved to position 4, the second switch to arrive on the multiple test contact will find battery potential thereon and its test relay or magnet 214 will not be energized. When the second 40 selector side switch was moved to position 3, a circuit was established from battery through the secondary stepping magnet 222, wiper 223 and interrupter 224 to ground. This circuit will be maintained and the brushes 209, 45 210 and 211 will be stepped from trunk to trunk until the contacts of an idle trunk are engaged, when current will flow through the left winding of magnet 214 in a direction to assist the current flowing through its right 50 winding, thus energizing the escape magnet and moving the side switch to position 4.

It is obvious from the preceding description in what manner succeeding selector switches would be operated. The secondary 55 magnet of the connector switch might be arranged to be substituted by a side switch wiper for the primary magnet in the circuit controlled by relay 215. It is believed this is obvious and will not require further description.

By means of the apparatus of Fig. 1 shown and described or otherwise indicated, the talking conductors 111 and 112 of the connecting circuit of Fig. 4 are extended to the calling line having a substation A, this 70 circuit being independent of the circuit previously had which may be called an instruction circuit for the operator from the said line. A conversational circuit is now complete including the said conductors and contacts of the switches of the system of Fig. 5 from the calling subscriber's line to the called subscriber's line thru the talking conductors 111 and 112 of the connecting circuit of Fig. 4 and contacts 62 and 244 of the 75 relay 63 of the said connecting circuit, and thru co-operating contacts of the plug and jack switch P1—J3 by means of which as has been described, connection is made with the called line LL shown in Fig. 1. The 80 ringing of the called substation may now proceed in the usual manner for manually operated systems.

The circuit of the impulse conductor 110 of Figs. 4 and 5, is controlled by contacts 85 108 of the relay 109, and these contacts remaining closed during successive sets of impulses until a series of selector switches of Fig. 5 are operated as described, to make connection with the calling line. The conversational circuit established thru the conductors and contacts of the switches of the system of Fig. 5 of the calling subscriber's line to the plug connecting circuit CP of Fig. 4, is now operative to cause the operation of the bridged subscriber's battery feed relay 231, which is now included in circuit with the subscriber's line thru the said contacts, the circuit including the subscriber's instrument and the central office source of 90 current. The relay 231 will thereupon attract its armatures upon the flow of current thru the said circuit and from the said source contacts 232 and 233 being closed. The contacts 232 being closed, a circuit will 95 be completed including the said contacts, a winding 235 of the relay 109 and now closed contacts 78 of the relay 63, together with the source of current. Current from the said source will flow over the said circuit operating the relay 109, which will attract its armatures closing the contacts 236 and 237, and opening the contacts 108, the mechanical arrangement being such that the contacts 237 are closed before the contacts 108 are opened. This in order to maintain the circuit of conductor 110 controlling the selective switch system of Fig. 5 closed, even though the original circuit for the said switches thru the contacts 108 are opened, 110 the circuit being maintained closed thru the contacts 237 and the winding of a relay 238 to the ground pole of battery. The relay 238 being included in this circuit, current will flow thru its winding and out 115 120 125 130

over the conductor 110, and the relay 238 will be operated, and the relay 205 of Fig. 5 will be maintained operated to hold the established connection. The relay 238 being operated will close contact 239 in the circuit of the calling subscriber's signal 230 which will not at this time be operated, because of the open contacts 234 of the relay 231, the said contacts being in its circuit.

10 The relay 109 being operated, as described, a holding circuit is established therefor including contacts 236 closed by its operation and now closed contacts 78 of the relay 65, the said holding circuit including a winding 241 of the relay 109.

15 The selective system of Fig. 5 having established connection with the contacts of the calling line, a circuit is completed for a winding of the cut-off relay of the calling line including contacts b_1 of the connector switch, circuit conductor b of the line circuit leading thru a winding 242 of the cut-off relay C of the line circuit, the said circuit including the central office 20 source of current, contacts of the selector switch system of Fig. 5 and the central office source of current. The cut-off relay C will thereupon be operated, opening its contacts 1 and 3 in the circuit of the line relay 6 to deenergize the said line relay, and the contacts 2 will be closed to connect the circuit conductors a and b of the line together, so that the increased potential of the conductor b may be duplicated on the conductor a in order to make the test contacts x and y of the multiple jack of the said calling line test busy to prevent the intrusion of another operator's connecting circuit. The line relay 6 of the line being deenergized, it will open its contacts 7, 8 and 9 to restore the relay 12 of the line circuit, and the relays 19 and 21 of Fig. 1, and 27, 32 and 34 of Fig. 3, together with relays 44, 49, 60 and 88 of Fig. 4; these relays being involved 25 in the connecting system for the instruction circuit which has been described, and in turn successively controlling various portions of the instruction circuit, each of the relays being controlled by preceding relays in the instruction circuit, and the contacts of the controlling line relay 6 being opened, these relays will be all restored to normal as will be apparent from the foregoing description, allowing the instruction circuit connecting links involved in the established instruction circuit connection to revert to the use of a subsequent incoming call.

30 The ringing of the called substation is initiated by the depressal of one of the keys K_1 , K_2 , K_3 or K_4 depending upon which station of a party line, if the called line is a party line, it is desired to signal, and the contacts 240 which are mechanically associated with all of the ringing keys will be

momentarily closed during the depressal of any of the ringing keys, these ringing keys being mechanically locked in ringing position. The ringing relay 63 is operated and the ringing proceeds. The circuit for the 70 ringing relay 63 includes its winding and the contacts 240, together with normal contacts 241 of the relay 83 and now closed contacts 233 of the relay 231, resistance coil 242 and now closed contacts 79 of the relay 75 65 together with the central office source of current. Upon the operation of the relay 63, the contacts 243 thereof are closed, bridging the contacts 240 of the ringing key to cause the locking circuit for the relay 63 80 independent of the said key contacts.

85 The contacts 244 and 62 of the relay 63 are now opened, opening the talking conductors leading to the plug P1 which is understood to be now inserted into the jack J3, and the contacts 245 and 246 leading from the key selected ringing generator, such as the generator G1, and the serially included central source of current as B1. Current from the said ringing generator 90 will flow thru the said ringing contacts 245 and 246 thru the talking conductors 61 and 247 leading to the called plug, and from thence thru the contacts of the plug and jack switch P1 and J3 and over the line 95 conductors 248 and 249 of the called line, and thru the windings of the called subscriber's telephone bell 250, ringing the said telephone bell. The called subscriber answering his telephone will remove his receiver from the hook, closing contacts 251 bridging his telephone transmitter across the telephone line, and current from the central source of current B1 flowing over the circuit for direct current thus established will operate the trip relay 252 in the plug connecting circuit CP of Fig. 4, causing it to close its contacts 253 to bridge the said contacts across the winding of the ringing relay 63 to deenergize the said relay and cause it to restore its armatures to normal, opening the ringing contacts 245 and 246 and the locking contacts 243, and closing the talking contacts 62 and 244. These last named contacts being closed, a 100 circuit is complete from the subscriber's substation apparatus thru the said contacts, and thru windings 89 and 280 of the bridged subscriber's battery feed relay 83 and the central office source of current. Current from the said source operating the said relay, will cause the contacts 241 in the circuit of the ringing relay 63 to be opened to prevent the reenergization of the said relay, and the contacts 82 to extinguish the signal lamp 105 110 115 120 125 130 84. The subscribers are now in conversational circuit and will so continue until the end of the conversational period, whereupon they will restore their receivers to their hooks, opening their respective line 130

- circuits. The opening of the called subscriber's line circuit and of the calling subscriber's line circuit will be evidenced in the operated plug connecting circuit CP, by 5 the lighting of the respective signal lamps for calling and called subscribers, 240 and 84, this being caused by the deenergization of the respective bridged battery feed relay for calling and called subscribers 231 and 83. 10 The operator upon observing the lighting signals will disconnect by removing the plug P1 from the called line jack J3, restoring the cut-off relay 71 of the called line to its normal condition and restoring the relay 65 15 in the plug connecting circuit to its normal deenergized condition. The relay 65 being restored, circuit controlling contacts 76, 77, 78 and 79 thereof, will be opened to release the apparatus of plug connecting circuit CP, the contacts 78 being operative to release the relay 103 which thereupon opens its contacts 104 in the circuit of the conductor 110 leading to the relay 205 shown in Fig. 5, the said relay 205 being thereupon restored to normal. The contacts of the relay 205 being opened, the apparatus of the selective switch system of Fig. 5 which is being held operative by the continued closure of these contacts, will be restored to normal 25 30 upon the opening thereof, and the switch involved in the established connection as has been described, will be restored to normal position.

I have described a specific embodiment of 35 my invention for the sake of conveying and understanding of the same, but I am aware that numerous and extensive departures may be made from the embodiment described without departing from the spirit of the 40 invention.

What I claim is my invention and wish to cover by U. S. Letters Patent is:—

1. In a telephone system, the combination 45 with an operator's instruction circuit for calling telephone lines, of a signaling circuit for the said instruction circuit, the said signaling circuit being under the control of subscribers' line apparatus, of an operator's connecting circuit, and manually 50 operated means to cause the said instruction circuit to be associated with the said connecting circuit, apparatus in the said connecting circuit operating under the control of the said signaling circuit to establish 55 a conversational circuit with the calling line, and manually operated means to cause the said connecting circuit to be connected with a called line.

2. In a telephone system, the combination 60 with telephone lines, of call receiving apparatus therefor, call means for connecting a calling line to an idle call receiving apparatus, a plurality of manually operated connection switches normally disassociated 65 from said call receiving apparatus,

said connection switches being manually selectable for use, and means responsive to the selection of said connection switches to inter-connect apparatus associated with said connection switches and a call receiving circuit in which an answered call resides, and governing means controlled thru the said connection to extend a connection from the manually selected switch terminals to terminals of the calling line, and means automatically responsive to the extension of the said connection, to isolate said call receiving circuit from the said calling and called lines and connection switch apparatus.

3. In a telephone system, the combination 80 with a plurality of telephone lines, a plurality of call receiving circuits therefor, intermediate call distributing means whereby a calling line is connected to an idle receiving circuit, an operator's key to associate an operator's telephone set with a call receiving circuit to which a calling line is connected, a plurality of connecting circuits manually selectable for use in connecting calling and called telephone lines normally 85 dissociated from said call receiving circuits, and means operative upon a given connecting circuit being taken for use by an operator and under the control of a connection switch connected to a called line, to temporarily associate apparatus in the said connecting circuit with the said call receiving circuit wherein the last attended call at the time resides, a line identifying conductor extended thru the said distributing means 90 and the said receiving circuit to apparatus in the said connecting circuit when the said connecting circuit is temporarily associated with the said call receiving circuit, whereby the said connecting circuit apparatus is 95 caused to extend a conversational circuit from the connected called telephone line to a calling telephone line, the said extended connection being independent of the previously established connection to the said 100 call receiving circuit, and means operable thereafter to dissociate the said connecting circuit and the said call receiving circuit.

4. In a call distributing system, a combination 115 with an operator's instruction circuit, of a calling telephone line connected thereto, a selective switching system and a connection switch individual thereto and under the control of an operator to make connection between the said selective switch 120 system and a called line, the said selective switch system being temporarily under the control of apparatus individual to the calling line and extended over the said instruction circuit to the selective switch system, 125 and means operable upon a connection being established between calling and called lines over the said selective switch system whereby the control over the said selective switch system by apparatus of the said 130

- line and instruction circuit is dissociated.
5. In a telephone system, telephone call indicating means, means to operate the said indicating means, an operator's set, a calling 5 telephone line controlling the said indicating means, means to cause the said telephone operator's set to be connected to an extension call circuit of the calling telephone line, manually operated switching apparatus,
- 10 automatically actuated apparatus operating under the joint control of the said manually operated switching apparatus and said calling line apparatus to cause a separate conversational circuit to be established be-
- 15 tween the calling telephone line and an operator's connection circuit whereby the operator may establish a connection between calling and called telephone lines independent of the initial call circuit apparatus.
- 20 6. In a telephone system, the combination with a main exchange switchboard and a plurality of substation telephones, telephone lines leading from the said substations to the main exchange, a plurality of 25 operator's positions at the main exchange, a plurality of operators' instruction circuits for each operator's position, call distributing circuits and apparatus to interconnect a calling subscriber's line circuit with an idle 30 one of said instruction circuits whereby an operator may be instructed concerning a desired connection by the subscriber on the said calling line, a plurality of link circuits at the said operator's position, each of 35 which is adapted to be manually selected for use by the operator, an automatic selective switch system under the control of apparatus in each of the said link circuits, connection switches to interconnect called telephone lines with the said link circuits, the 40 said connection switches being operator controlled and apparatus in the said link circuit operable upon a connection being made between the said link circuit and a called 45 telephone line to associate the said selective switch system and a selective switch controlling conductor of the said instruction circuit, to control the operation of the said selective switches, means to cause the said 50 switches to operate to connect the said link circuit talking conductor with the talking conductors of the calling telephone line whereby the calling and called telephone lines are placed in conversational circuit, 55 and means to isolate the call distributing and operator's instruction circuit from the connection.
7. In a telephone system, the combination with a plurality of telephone lines, of an 60 operator's position for interconnecting the said telephone lines, of a link circuit at the said operator's position, of a plurality of sets of conductors for the telephone system, one conductor of each set being associated 65 with each telephone line to numerically

identify the telephone line, a call distributing system to extend a calling telephone line to an instruction circuit on an operator's position on the switchboard and to extend a line identifying conductor under the control 70 of the said group of conductors identifying the telephone line to the said operator's position, means to cause the said identifying conductor to be associated with a said link circuit to operate selective switches 75 with which the said link circuit is associated whereby the said link circuit is connected to a calling telephone line over a path independent of the said call distributing system and instruction circuit, means thereafter operative to dissociate the said link circuit and the said call distributing system and instruction circuit, and connective means for the said link circuit to interconnect the said link circuit with a called telephone line.

8. In a telephone system, the combination with calling and called telephone lines, of a plurality of groups of link circuits for interconnecting the calling and called telephone lines of an instruction circuit for each group of link circuits, call distributing means to extend a calling telephone line to one of the said instruction circuits and a selective switch system under the control of 95 an operator for interconnecting a manually selected one of the link circuits associated with the said instruction circuit with the calling telephone line, the said established connection being independent of the connection between the calling telephone line and the said instruction circuit, line identifying means extended from the calling telephone line over the said call distributing system, an instruction circuit also controlling 100 the said selective switch system, and a connection switch under the control of the operator to connect the other end of the said link circuit with a called telephone line to 105 interconnect the called and calling telephone lines.

9. In a telephone system, the combination with calling and called telephone lines, of a plurality of groups of link circuits for interconnecting the calling and called telephone lines, of an instruction circuit for each group of link circuits, call distributing means to extend a calling telephone line to one of the said instruction circuits and a selective switch system under the control of 115 an operator for interconnecting a manually selected one of the link circuits associated with the said instruction circuit with the calling telephone line, the said established connection being independent of the connection between the calling telephone line and the said instruction circuit, line identifying means extended from the calling telephone line over the said call distributing system, an instruction circuit also controlling 120 the said selective switch system, and a connection switch under the control of the operator to connect the other end of the said link circuit with a called telephone line to 125 interconnect the called and calling telephone lines.

130

selective switch system, a connection switch under the control of the operator to connect the other end of the said link circuit with a called telephone line to interconnect the 5 called and calling telephone lines, and means operable under the connection of the said calling telephone line and the said link circuit to dissociate the said link circuit and the said instruction circuit.

10. In a telephone system, the combination with a plurality of telephone lines, one of which is a calling telephone line and one of which is a called telephone line, an operator's interconnecting link circuit for interconnecting the said calling and called telephone lines, means to extend a calling telephone line to the operator's position at which the said link circuit is located, an operator's telephone set for the said position, means to associate the telephone set with the said calling line over the said calling line extension whereby the operator may be instructed as to the desired called line, operator controlled means to interconnect the called telephone 25 line with the calling telephone line over a conversational circuit entirely independent of the calling line extending means, said interconnecting means including a manually operated terminal and an automatically operated terminal, said manually operated terminal being manually selectable, and adapted to associate the said interconnecting means with the called telephone line, and said automatically operated terminal being 35 adapted to be actuated responsive to the manual selection of the said manually operated terminal.

11. In a telephone system, the combination with a plurality of telephone lines, one of which is a calling telephone line and one of which is a called telephone line, an operator's interconnecting link circuit for interconnecting the said calling and called telephone lines, means to extend a calling telephone line to the operator's position at which the said link circuit is located, an operator's telephone set for the said position, means to associate the telephone set with the said calling line over the said calling line extension whereby the operator may be instructed as to the desired called line, operator controlled means to interconnect the called telephone line with the calling telephone line over a conversational circuit entirely independent of the calling line extending means, an automatically operated terminal and a manually operated terminal for the said interconnecting means, said automatically operated terminal being selected to interconnect the calling line with the said interconnecting means responsive to the manual selection of the said manually operated terminal, and means to interconnect the interconnecting means to the called line by the operation of the manually operated terminal, the

said conversational circuit being under the control of apparatus associated with the calling telephone line extending means.

12. In a telephone system, the combination with a plurality of telephone lines, one of which is a calling telephone line and one of which is a called telephone line, an operator's interconnecting link circuit for interconnecting the said calling and called telephone lines, means to extend a calling telephone line to the operator's position at which the said link circuit is located, an operator's telephone set for the said position, means to associate the telephone set with the said calling line over the said calling line extension whereby the operator may be instructed as to the desired called line, and operator controlled means to interconnect the called telephone line with the calling telephone line over a conversational circuit entirely independent of the calling line extending means, the said conversational circuit being under the control of apparatus associated with the calling telephone line extending means, and means thereafter to relieve the interconnecting means of the said control.

13. In a telephone system, a plurality of telephone lines leading from substations to an exchange, of call distributing apparatus at the exchange to extend a calling line to an operator's idle call receiving circuit, an operator's link circuit adapted to interlink calling and called lines in conversational circuit, two groups of circuit conductors for the lines, each group containing ten circuit conductors, each conductor representing a numerical digit, a pair of conductors adapted to be associated with the said groups of conductors, each of the said pair leading to a particular circuit conductor of different groups whereby the pair of circuit conductors may be identified by the numerical digit designations of group conductors with which they are connected, means to associate the said pair of conductors with calling line apparatus whereby the calling line may receive a numerical two digital designation and a relay serially included in circuit with the said pair of conductors, the said conductors of the groups connected thereto, a commutating apparatus for the last-named conductors together with a source of current whereby the said relay may be operated in a characteristic manner, contacts for the said relay and a circuit conductor leading thru the said contacts and extended with the conductors of the line circuit to the said call receiving circuit, and selective switching apparatus adapted to be associated with the said call receiving apparatus operating under the control of the said extended conductor to directly establish a circuit connection between the calling line and operator's link circuit, the said connection being inde-

pendent of the connection of the said call distributing apparatus, and operator controlled means to extend the connection from the said link circuit to the terminals of a 5 called telephone line.

14. In a centrally operated telephone system, the combination with a plurality of telephone lines, of call instruction circuits for the said lines, link circuits for establishing a connection between calling and called 10 lines under the control of apparatus in the said instruction circuits, a manually selectable manual terminal for each of the said link circuits, and an automatically operable 15 terminal for each of the said link circuits, said manual terminal controlling the said automatic terminal, and automatic means responsive to the operation of the said terminals to render the said interconnecting 20 circuit and instruction circuit independent.

15. In a centrally operated telephone system, the combination with a plurality of telephone lines, of an operator's instruction circuit for the said lines, of an operator's 25 line interconnecting circuit having two adjustable terminals, one of the said terminals being a manually operated terminal and the other terminal being automatically operated, and means operative under the joint 30 control of the manually operated terminal and the automatically operated terminal to connect the said interconnecting circuit to a called line, and to operate the other adjustable terminal to make connection with the 35 calling line to interconnect the calling and called line.

16. In a centrally operated telephone system, the combination with a plurality of telephone lines, a circuit conductor adapted 40 to be placed under the control of line apparatus of any of the said lines, of an operator's instruction circuit for the said lines, means to interconnect a calling line to the said instruction circuit, line identifying 45 means adapted to be associated with the said calling line and the circuit conductor under the control of the said line, an operator's interconnecting circuit having a manual and an automatic adjustable terminal 50 for called and calling lines, said automatic terminal being operated over the said conductor under the control of the said line identifying means to make connection with the calling line, and said manual terminal 55 being under the control of the attendant operator.

17. In a centrally operated telephone system, the combination with a plurality of telephone lines, a circuit conductor adapted 60 to be placed under the control of line apparatus of any of the said lines, of an operator's instruction circuit for the said lines, means to interconnect a calling line to the said instruction circuit, line identifying 65 means adapted to be associated with the said

calling line and the circuit conductor under the control of the said line, and an operator's link circuit having an operator controlled terminal for making connection with a called telephone line and an automatic 70 selective terminal for making connection with a calling telephone line, said last-named terminal being under the control of the said line identifying means over the said conductor.

18. In a centrally operated telephone system, the combination with a plurality of telephone lines, or an operator's instruction circuit for the said lines, means to interconnect a calling line to the said instruction circuit, line identifying means adapted to be associated with the said calling line and the circuit conductor under the control of the said line, and an operator's link circuit having an operator controlled terminal for making connection with a called telephone line and an automatic selective terminal for making connection with a calling telephone line, said last-named terminal being under the joint control of the 90 said line identifying means over the said conductor and the said operator controlled terminal connection between the said link circuit and the said called line.

19. In a centrally operated telephone system, the combination with a plurality of telephone lines, of a group of call receiving circuits for each operator's position, of a relatively large number of interconnecting link circuits for the said operator's position, means 100 to connect a calling line to one of the said call receiving circuits, adjustable terminals for each of the said link circuits to connect the calling and called telephone lines, operator controlled means to associate any incoming call circuit with any of the said link circuits to control one of the adjustable terminals for calling telephone lines of the said link circuit, said associating means being operative upon the adjustment of the called 110 terminal by the operator, and automatic means to dissociate the said call receiving circuit and the said link circuit after the calling adjustable terminal has connected to the calling telephone line, whereby the said 115 call receiving circuit may be available for the use of other calling lines of the system, and a connection be maintained between the said calling and called telephone lines associated with the said link circuit over the said link 120 independent of the said call receiving circuit.

20. In a centrally operated telephone system, the combination with a plurality of telephone lines, line identifying means for the 125 said telephone lines of a group of operator controlled link circuits for interconnecting telephone lines of a relatively small group of call instruction circuits for the said group of link circuits, the said group of link cir- 120

cuits and the said group of call circuits being individual to an operator's switchboard section, means to cause the calls to be associated with the operator's telephone set over the 5 said call circuits, and means operative when the operator subsequently connects a terminal of the said link circuit with a called telephone line to cause, first, the other terminal of the said link circuit to directively seek 10 and connect with the calling telephone line under the control of identifying means for the said telephone line operable over a conductor of the said instruction circuit, and second, to thereafter dissociate the said instruction circuit and the said link circuit. 15

21. In a telephone system, a plurality of telephone lines, operators' positions, link circuits thereat, each link circuit terminating at one end of a manual switch and terminating at its other end in an automatic switch, a rotary impulse machine common to said lines and arranged to transmit impulses in accordance with the designation of any line when calling, and means for causing 25 an automatic switch to extend a selected link circuit to a calling line in response to selective impulses from said impulse machine.

22. In a telephone system, a plurality of 30 telephone lines, operators' positions and link

circuits associated therewith, said link circuits each being provided at one end with a manual switch and at the other end with an automatic switch, and a rotary impulse machine common to said lines and effective 35 to selectively operate an automatic switch of a selected link circuit under the control of the calling line to cause said automatic switch to be connected to a calling line responsive to the connection of said manual 40 switch to a wanted line.

23. In a telephone system, a plurality of telephone lines, operators' positions and link circuits associated therewith, said link circuits each being provided at one end with 45 a manual switch, numerical automatic switches accessible to the other end of each link circuit, and a rotary impulse machine common to said lines and effective to selectively operate the automatic switches associated with a link circuit in response to impulses therefrom corresponding to the designation of the calling line, the operating of said numerical switches being controlled by the connection of a manual switch of a link 50 circuit to the wanted line.

In witness whereof, I hereunto subscribe my name this 19th day of January, A. D. 1918.

FRANK M. SLOUGH.
